UNITED STATES PATENT OFFICE.

JOSIAH W. SHERWOOD AND JOHN W. SHERWOOD, OF GRAND RAPIDS,
MICHIGAN.

MACHINE FOR TURNING CARRIAGE-BOWS.

SPECIFICATION forming part of Letters Patent No. 364,682, dated June 14, 1887.

Application filed January 8, 1886. Serial No. 188,040. (No model.)

To all whom it may concern:

Be it known that we, JOSIAH W. SHERWOOD and JOHN W. SHERWOOD, citizens of the United States, and residents of Grand Rapids, in the county of Kent and State of Michigan, have invented a new and useful Machine for Turning Carriage-Bows, of which the following is a specification.

Our invention relates to improvements in machines for forming and sandpapering carriage-bows or bow-slats and other irregular cylindrical wood-work in which a rotating cylinder carrying the cutting tool or sand-paper operates in conjunction with suitable mechanism for slowly rotating the material while in contact with said cylinder, and also guiding said material so that it will be cut to the required form or uniformly polished by the sand-paper.

20 The objects of our invention are to provide means whereby the machine may be readily adapted for either forming the material by means of cutting-knives or sandpapering the material after the forming; also, means whereby the material may be prevented from springing away from the cutter or sand-paper; also, to provide means whereby the machine may be readily adapted to operate upon a variety of forms, as will more fully appear hereinafter.

25 30 We obtain these objects by the mechanism illustrated in the accompanying drawings, in which—

Figure 1 is a vertical section of the machine. Fig. 2 is a section at right angles to Fig. 1, with 35 the frames G G broken away. Fig. 3 shows a cylinder arranged with knives for forming the material. Fig. 4 is an end view of the same. Fig. 5 is a detail view of the spindle or center with cam attached. Fig. 6 is a perspective 40 view of a pair of parallel backing-rolls and flexible bearings for the same, and Fig. 7 shows detail views of different forms of cams.

Within a suitable frame, A, is suspended a cylinder, B, provided with the usual shaft, a, 45 rotating in suitable boxes, and having a driving-pulley, b, attached. Said cylinder is also provided with the usual means of attaching sand-paper to its surface, and a casing, a', and a pipe, a'', for conveying away chips and dust. 50 Across the top of the frame A is supported a shaft, C, which supports the arms D D', and the pulleys E E', upon which they are all free

to rotate, the pulleys being firmly attached to each other. In the lower end of the arm D is journaled a back spindle, c, provided with either a square or spur point, f. Said spindle is also provided with a suitable cam, e, secured to the spindle by a screw, e', and is connected near its outer end to a lever, g, which is forked at both ends and fulcrumed to a short arm, g', 60 on the arm D, the lever g having attached to its opposite end a rod, h, passing through a spring, l, which maintains back spindle, c, in its normal position. Formed on the end of rod h is a ring, h', for drawing back the said rod, 65 and thereby actuating lever g, which withdraws from the material the back spindle, c, and thus releases the said material when required. On the outer end of spindle c is secured a pulley, d', which, through belt K' and 70 pulley E', (on shaft C,) imparts motion to the said spindle.

Journaled in the lower end of the arm D' is a suitable driving-spindle, c', having at its outer end a pulley, d, and near its inner end a detachable cam, e', secured to the said spindle c' by a screw, e'', (similar to screw e' of cam e,) and of a form to correspond with the end of the completed slat. The said spindle c' terminates at its inner end either in a suitable spur, f, or a plug, f', to hold and rotate the material. Pivoted to suitable lugs on the frame A are retaining-hooks d' d'', which pass over and hold, allowing slight play, the lower ends of the arms D D'. Swinging on the lower 85 ends of the arms D D' (or, if convenient, to the shaft C) are two other arms, F F'. To the lower end of each swings by a pivot, j'', a yoke, G, having arms j j, swinging on pivots j', the said arms j j being slotted to permit the passage 90 and suitable play of rods l' l'', which also pass through springs l' l'', which, by their tension exerted against the arms j j, serve to maintain the rolls k k in contact with each other.

H H are guide-posts having curved outer 95 surfaces to correspond with the periphery of the cylinder B, and are secured by bolts m m passing through slotted holes, as shown in dotted lines, Fig. 1, and are adjustable in a direction at right angles to the axis of the 100 said cylinder by means of hand-screws n n. Against the faces of the said posts H H the cams e e', which are secured to the spindles c c' by set-screws e'', revolve, (through the me-

dium of shaft C,) and they impart an oscillating motion to the parts suspended from the arms D D' and F F'. The said cams are of such form as illustrated in Fig. 7, in which 5 1 represents a disk which is used when a slat of circular form is needed; 2, a cam when one of hexagon shape is required; 3, an elliptical form; 4, a triangular shape with curved sides, and 5 shows a convexo-convex outline. Other 10 forms will suggest themselves as occasion may require.

The arms F F' are connected to the treadle I in any suitable manner, that shown in Fig. 1 representing only one side of the machine, 15 and consists of a cord, o, attached at one end to the end of the arm F', passing over a pulley, p, and fastened at the other end to the said treadle, which, on being depressed, lifts the arm F' and its attachments from the cylinder 20 B. A similar device on the opposite side of the machine controls arm F. The said arms F F' are also attached to the arms D D' by means of the cords o', which admit of a slight separation of the arms D D' and F F'.

25 Motion is imparted to the spindles c c' from the shaft a by means of the belts K' K K' and pulleys E', E, d, E², and d', arranged as shown. By such arrangement the belts do not interfere with the movements of the arms, and are 30 kept tight regardless of the position of said arms.

Figs. 1 and 2 show the cylinder B with a sheet of sand-paper, x, attached, as shown, when the said cylinder is to be used for sand- 35 papering. Figs. 3 and 4 show the cylinder B' arranged with spiral knives for forming the slat from the blank.

The cylinder B', Figs. 3 and 4, is preferably 40 of cast-iron, with a turned surface having channels r r, in which are knives s s. Said channels are hollowed in front of the knives, as shown, to allow the chips to escape. Said knives and channels are arranged spirally on the surface of the cylinder B', so that the material will at all times have a bearing against 45 the turned surface of said cylinder.

The operation of our devices is as follows: Having the cylinder B' in the machine and 50 cams of suitable form on spindles c c', a suitable piece of material is adjusted between the said spindles, the guide-posts are drawn forward by means of the hand-screws n n, and the machine is set in motion. A slow rotary motion will be imparted to the said piece of material, together with the spindles, and the cams, 55 resting upon the guide-posts, will cause the arms D D' and all parts attached to oscillate according to their form and position. As the guide-posts are run back by the hand-screws 60 the knives on the cylinder B' will cut away portions of the material until the bolts m stop the movement of said post by coming in contact with the ends of the slots in which they move, the result being that the material will 65 conform throughout its length to the shape of the cams used, and be of a form defined by right lines drawn from end to end and parallel

with the axis. On completion of the work the retaining-hooks d d² are thrown back and the finished slat is removed. 70

If desired, the posts may remain stationary and the material rest against the turned surface of the cylinder until the cams come in contact with the posts, the spiral form of the knives preventing jar and heavy strains upon 75 the material, for the reason that they begin to cut at one end first.

As the axis of the material is parallel with that of the cylinder, the spiral form of the channel and knife prevents the material from catching in the said channel. 80

The rolls k k rest upon the material in two lines parallel to and nearly opposite the cylinder B', and prevent jarring and springing of the material. By the arrangement of the pivoted yoke, arms, and springs described each 85 roll is free to follow the surface of the material regardless of its form. When the forming operation is completed, the hooks d d² are thrown back and the treadle I is depressed, which first lifts the rolls from the material 90 and then the material from the cylinder, when the material can be removed by withdrawing the spindle c by means of the rod h. The sand-papering operation is substantially the same, except that the cylinder B, as described, is 95 used.

What we claim and wish to secure is as follows:

1. The combination of the cylinder B, the supporting arms D D', carrying the spindles c c', cams e e', in conjunction with the curved guide-posts H H, hand screws n n, and retaining-hooks d d², as shown and described.

2. A rotating cylinder having attached either sand-paper or knives, in combination 105 with the rotating spindles c c', for holding and rotating the material to be operated upon, and rolls k k, adjusted in spring-bearings and independent of each other, arranged to prevent the said material from springing, substantially 110 as described.

3. The combination of the guides H H, hand-screws n n, spindles c c', cams e e', and yielding rolls k k, arranged to prevent the material 115 from springing, all serving to maintain the said material in position while being operated upon, as shown and described.

4. The spindles c c', adapted to hold and rotate the material, and a cutting cylinder 120 adapted to operate upon the said material, in combination with the rolls k k, the arms D D', and retaining-hooks adapted for temporarily holding the said arms and the material in position, substantially as described.

5. The combination of the arms D D', F F', 125 the pivoted yokes G G, having the pivoted slotted arms j j, springs l l', rods l' l'', and rolls k k, independent of each other, as shown, and for the purpose described.

JOSIAH W. SHERWOOD.
